corporation of Illinois

Application March 4, 1939, Serial No. 259,752

4 Claims. (Cl. 62—126)

This invention relates to the art of refrigeration and has particular reference to a new and improved form of heat absorbing or evaporator element which, as illustrated, is particularly designed for use in the provision compartment of household refrigerators, said evaporator being provided with a wall adapted to receive liquid holding trays and with an extensive heat absorbing surface over which air in the provision compartment of such refrigerator is adapted to circulate.

Heretofore, evaporators for domestic refrigerators have been designed so that the internal walls thereof define a part of a freezer compartment and so that the external walls thereof provide a heat absorbing surface and shield the contents of the freezing compartment from circulating air within the provision compartment.

It is a primary object of this invention to provide a new and improved form of evaporator which may be constructed in two more or less independent parts, one part of which is primarily adapted and designed for ice freezing and the other part of which is primarily adapted and designed for air cooling.

Another object of the invention is to provide a new and improved form of evaporator with a great amount of heat absorbing surface over which the air in the provision compartment may circulate.

Another object of the invention is to provide an evaporator with heat absorbing surfaces internally and externally thereof and over which the air in the provision compartment is adapted to circulate.

Another object of the invention is to provide a new and improved form of evaporator which may be adapted for producing refrigeration at two different temperatures simultaneously.

Other objects and advantages of the invention will be apparent from a consideration of the following specification taken in conjunction with the accompanying drawings of which there are two (2) sheets and wherein:

Fig. 1 is an elevational view partially broken away and partially in section and illustrating a refrigerator of the household type embodying a refrigerating system including an evaporator of the type herein contemplated;

Fig. 2 is an enlarged front elevational view of

an evaporator or heat absorbing element embodying this invention;

Fig. 3 is a plan view of the evaporator illustrated in Fig. 2; and

Fig. 4 is a horizontal sectional view through the evaporator taken in the plane along the line 4—4 of Fig. 2 looking in the direction of the arrows.

In Fig. 1 there is illustrated a household refrigerator having a heat insulated provision compartment 10, an apparatus compartment 12 and a refrigerating system including a condensing unit assembly arranged in the apparatus compartment 12, and an evaporator arranged in the provision compartment 10 and operatively connected to the condensing unit assembly. The condensing unit assembly may comprise, as illustrated, conventional elements of refrigerating systems, such as, a motor 14, a compressor 16 adapted to be driven by the motor, a condenser 18, a refrigerant expansion control comprising a high side float 20 and an electric cord 22 adapted to be connected to a suitable electric receptacle so as to supply current to the motor 14 for operating the same. The supply of current to the motor 14 may be under the control of a thermostatic and manually adjustable switch and cold control 24 which includes a thermostatic element 26 thermally associated with a part of the evaporator, said switch 24 being adapted normally to open and close the motor circuit in accordance with predetermined temperature variations of the evaporator, thereby effecting the operation of the refrigerating system in such a way as to maintain the temperature of the provision compartment within certain fairly definite limits.

The evaporator 25 is connected to the condensing unit assembly by a liquid refrigerant supply line 30 which may consist of a capillary tube and so as to be supplied with liquid refrigerant under the control of the refrigerant expansion control 20, and the upper part of the evaporator is connected to the intake side of the compressor by return suction line 32 which, as illustrated, may be arranged in heat exchange relationship with the liquid refrigerant supply line 30.

In general, the evaporator 28 consists of a plurality of sections or parts, namely, the freezing or low temperature section, indicated generally

at 34, and the air cooling or relatively high temperature section, indicated generally at 36, one of said sections being arranged within and supported by the other of said sections, although, this relative arrangement of the sections is optional as the sections may be arranged and supported independently. The box cooling section, as illustrated (referring particularly to Figs. 3 and 4), may consist of a U-shaped heat absorbing element open at the top and at the bottom and comprising a lower liquid distributing header 38 and an upper header 40 interconnected by a plurality of refrigerant ducts 42.

The walls of the element or section 36 may be formed from two sheets of metal having corrugations or ducts formed therein, prior to assembly, welded or brazed together and then bent into a U-shaped form so as to provide the headers 38 and 40 extending from one end thereof to the other and interconnected by refrigerant ducts 42. The header 38, at each end thereof, is adapted to be supplied with liquid refrigerant by a liquid supply tube 44, and opposite portions of the upper header 40 are connected by a cross tube 46 to which the suction line 32 is connected for the purpose of conducting refrigerant vapor and oil back to the intake side of the compressor. The system is charged with a suitable quantity of liquid refrigerant, including a supply of oil in the compressor and during the operation of the system the refrigerant expansion control is adapted to supply liquid refrigerant to the evaporator so as to maintain the liquid level thereof approximately somewhere between the upper and lower limits of the header 40. As previously explained, the air cooling section 36 is open at the top and bottom so that air in the provision compartment 10, upon circulation, will pass over both the internal surface 48 and the external surface 50 of the heat absorbing element 36. Both of these surfaces, it will be observed, are U-shaped and it will also be observed that these surfaces are provided not only at the sides of the evaporator but at the back thereof. As a consequence of the air movement over the surfaces 48 and 50, refrigerant in the headers 38 and 40 and the ducts 42 will be vaporized thereby effecting the absorption of heat from such circulating air. The element 36 may be supported from the top of the provision compartment 10 by means of brackets 52.

The low temperature or ice freezing section 34 may consist of a sleeve 54 permanently closed at the back and closed at the front by a door 56 pivotally suspended on hinge means 58 provided on the forward edge of the air cooling section of the evaporator 36 at one side thereof. The door 56 preferably is of such size as to conceal the entire front of the evaporator. The front edges of the sleeve 54 may be provided with an annular gasket 60 so as to effectively seal the inside of the sleeve 54 when the door 56 is closed. The door 56 and sleeve 54 may be constructed of metal or of some insulating material. The sleeve 54, it will be observed, is arranged within the space partially enclosed by the air cooling section 36 and may be supported from the side walls thereof by means of brackets 62. The sleeve 54 and door 56 define a closed compartment or zone in which the heat absorbing means of the low temperature or ice freezing evaporator section is arranged. As illustrated in Fig. 4, the heat absorbing part of the low temperature evaporator element may consist of one or more refrigerator shelves 64, each shelf consisting of a

flat metallic plate 66 having a refrigerant duct or tube 68 thermally associated with the underside thereof. The plates 64 may be provided with upturned lugs 70 at the sides thereof and by means of which such plate 66 may be suspended from the inside walls of the sleeve 54. As shown in Fig. 2, there may also be provided within the sleeve 54 a nonrefrigerated shelf 72 suitably supported from the side walls thereof and arranged between upper and lower refrigerated shelves 66. Also, the bottom inside wall of the sleeve 54 may be formed to provide a shelf. Such shelves are adapted for supporting liquid holding trays, such as ice trays. The shelves 66 have a refrigerant duct thermally associated therewith and particularly adapted for fast freezing of ice. The shelf 72 may be made removable so as to provide an enlarged space within the sleeve 54 suitable for the storage of frozen foods.

The capillary tube 30 may be arranged so that a part 74 thereof is thermally associated with the underside of the upper one of the refrigerated shelves 66 and also so that a part or length of such capillary tube is arranged in heat exchange relation with a length or part of tube or duct 68 likewise secured to the upper side of the shelf 66. That part 74 of the refrigerant tube or duct arranged on the underside of the upper one of the shelves 66 is simply a continuation of the capillary or liquid refrigerant supply tube 30 and liquid refrigerant after passing through part 74 is conducted by a downwardly extending tube part 76 to one end 78 of a U-shaped duct 68 thermally associated with the underside of the lower one of the shelves 66. The other end of such duct 68 is connected by a tube or conduit 80 to one end 82 of the duct 68 thermally associated with the underside of the upper one of the shelves 66, and refrigerant after passing through the duct 68 of the upper shelf is discharged into a coupling or T 84 from which the conduits 44 return it to the ends of header 38. The direction of the refrigerant flow to the evaporator is indicated by the arrows and is as follows:

From the refrigerant expansion control 20 liquid refrigerant flows through the tube 30 thence through the part 74 thereof arranged on the underside of the upper shelf 66, thence through the duct 68 associated with the lower shelf 66, thence through the duct 68 associated with the upper shelf 66, thence into T 84 and branch conduits 44 to the lower header 38, thence through lower header 38 and upwardly through ducts 42 into upper header 40, thence through cross tube 46 and suction line 32 to the intake side of the compressor.

If a refrigerant such as SO_2 (sulphur dioxide) is used in this system the absorption of heat in all parts of the evaporator will take place at substantially the same temperature level and in order to effect the freezing of water within the low temperature section 34 and the storage of frozen foods therein this temperature level would have to be below 32° F . However, while this evaporator may be used in a system having a single refrigerant such as SO_2 therein, it is contemplated that the absorption of heat in the freezing section 34 should take place at a lower temperature level than the absorption of heat in the lower evaporator section 36. In the present instance, this may be readily accomplished by the use in the system of a refrigerant medium consisting of a liquid which comprises a mixture or solution of two or more refrigerant compo-

nents, both of which components will vaporize in the evaporator at the temperature level at which the system operates, said liquid having a different boiling point than that of its components. Examples of refrigerant mediums having a mixture of two or more components are:

Sulphur dioxide (SO₂) and dichlorodifluoromethane (CCl₂F₂) commonly known as F-12; and

Sulphur dioxide (SO₂) and trichloromonofluoromethane (CCl₃F) commonly known as F-11.

For further examples of suitable refrigerant consisting of two or more components, reference may be had to the application of Earl F. Hubacker, Ser. No. 179,249, filed December 11, 1937, for "Method of and apparatus for heat transfer" wherein such refrigerants are broadly disclosed and claimed.

It will be observed that refrigerant passes through the sections 34 and 36 in series and that there are no restrictions between the two evaporator sections so that evaporation of refrigerant must take place at substantially the same suction pressure. When using the foregoing refrigerant consisting of two or more components, part of the refrigerant mixture will be evaporated in the freezing section 34 and the liquid refrigerant not vaporized in the freezing section 34, as well as the vaporous refrigerant generated in 34, will be delivered to the air cooling section 36. While the percentage composition of each of the components or constituents of the mixture will depend upon the temperature effect desired in each section of the evaporator, we may assume for purposes of illustration the use of a refrigerant mixture comprising a five to ten percent solution, by weight, of F-12 to SO₂. With a refrigerant such as this the absorption of heat may take place in the freezing section of the evaporator at a temperature level of from 0 to 10° and the absorption of heat in the air cooling section of the evaporator may take place at a temperature level of from 25 to 30° F. In the freezing section 34 of the evaporator, due to the fact that the liquid contains five to ten percent of F-12 which is more volatile than SO₂, the absorption of heat by the refrigerant will effect the vaporization of all or substantially all of the F-12 as a result of which the liquid refrigerant fed to the air cooling section of the evaporator will consist of pure or substantially pure liquid SO₂. Due to the percentage of F-12 which is present in the liquid refrigerant in the freezing section 34, the temperature at which vaporization of the liquid will take place will be materially lower than the temperature at which vaporization of pure SO₂ will take place as a result of which heat absorption will take place in the freezing section 34 at a materially lower temperature than that at which the absorption of heat takes place in the air cooling section 36.

While I have illustrated one method by which two temperature evaporation may be effected, I do not intend to limit myself to the production of two temperature evaporation in accordance with the method just disclosed as other methods of effecting two temperature evaporation heretofore known in the art may be used in connection with my evaporator design so that the section 34 will operate at a lower temperature level than the section 36. For a better understanding of the method of producing two temperature refrigeration by the use of a binary refrigerant, reference may be had to French Patent No. 75

815,712, issued July 21, 1937, to Borg-Warner Corporation.

Due to the fact that both the inside and outside surfaces of the walls of the air cooling section of the evaporator are exposed to the circulating air within the provision compartment, it will be apparent that I have provided a greatly increased cooling area at practically no additional cost, that the absorption of heat is more efficiently carried on by the air cooling section of the evaporator due to the fact that the air passes in heat exchange relationship with both sides thereof, also, it will be observed that due to the particular arrangement of the walls of the air cooling evaporator that the air cooling surface extends not only on the sides of the evaporator but also at the back thereof. For the amount of space occupied by this evaporator, there is considerably more area of heat absorbing surface than there is in conventional evaporators. Also, there is greatly increased cooling surface and, also, due to the fact that a separate evaporator is provided for freezing ice, the temperature at which the air cooling evaporator will be operated may be considerably higher than that heretofore utilized and yet obtain a lower box temperature as well as a relatively higher humidity of the air within the box. This construction enables the use of fins to be dispensed with. Of course, the walls of the air cooling section of the evaporator should be spaced from both the side and back walls of the provision compartment so as to expedite the circulation of air over both the inside and outside surfaces of the walls of the evaporator.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. Refrigerating apparatus comprising a provision compartment having an evaporator element arranged therein, said evaporator element comprising continuous vertical heat absorbing walls provided by sheet metal arranged in a form of a horizontal U and having substantially all of the surface on both sides of said wall exposed to the circulating air within said provision compartment, the space between said walls being open at the top and bottom thereof adjacent said walls.

2. Evaporator construction including a U-shaped evaporator element, said element comprising vertical walls and including a lower liquid distributing header and an upper header interconnected by refrigerant passages, the space between said walls being open at the top and bottom thereof adjacent said walls, means for supplying liquid refrigerant to said evaporator comprising a branch liquid line having a part connected to each end of said liquid header, and means for conducting vaporous refrigerant from said evaporator comprising a suction conduit connected with said upper header.

3. Refrigerating apparatus including an evaporator having a plurality of sections arranged so as to be supplied with liquid refrigerant in series, one of said sections comprising a vertical wall having a refrigerant passageway thermally associated therewith, and the other of said sections comprising a horizontal wall having a re-

frigerant passage thermally associated therewith, said vertical wall arranged in the shape of a U being open at the top and bottom, the periphery of said horizontal wall being spaced inwardly of said vertical wall so as to permit air to circulate over both sides of said vertical wall throughout the entire extent thereof.

4. In an evaporator construction for a refrigerator including a plurality of evaporator sections connected in series, one of said sections being adapted to produce refrigeration at a first temperature and the other of said evaporator sections being adapted to produce refrigeration at another temperature, one of said sections comprising a vertically arranged wall formed with refrigerant passages therein, the other of

said sections comprising a horizontally arranged wall provided with means defining a refrigerant passage thermally associated therewith, said arrangement being particularly characterized by 5 the fact that at least a major portion of the periphery of said horizontal wall is spaced inwardly from said vertical wall to provide for the circulation of air on both sides of said vertical wall, a sleeve embracing said horizontal wall portion 10 for shielding the same from said circulating air, and means for delivering refrigerant to a first one of said sections and for withdrawing vaporous refrigerant from the other one of said sections.
